UNITED STATES PATENT OFFICE.

ALBERT F. SCHWERD AND ASA W. EMRICK, OF ALLEGHENY, PENNSYLVANIA.

WOODEN COLUMN.

SPECIFICATION forming part of Letters Patent No. 657,836, dated September 11, 1900.

Application filed May 8, 1898. Serial No. 715,968. (No model.)

To all whom it may concern:

Be it known that we, ALBERT F. SCHWERD and ASA W. EMRICK, citizens of the United States of America, residing at Allegheny, in the county of Allegheny and State of Pennsylvania, have invented certain new and useful Improvements in Columns, of which the following is a specification, reference being had therein to the accompanying drawings.

10 This invention relates to certain new and useful improvements in wooden columns, and has for its object to construct such columns of separate strips or sections which are locked together by means of interlocking joints.

15 The invention specifically relates to the shaft of the column, each of the strips or sections from which the said shaft is formed being provided at their one engaging face with a tongue and on their other engaging face 20 with a groove to receive the tongue of the adjoining strip or section. These tongues project outwardly at an incline and the grooves are similarly shaped in order that when the tongues are in engagement with the grooves 25 the sections will be practically wedged together in a manner which will prevent the destruction of the column either by interior or exterior pressure upon the same.

It is a further object of our invention to 30 construct a column-shaft which will be applicable in general to all of the orders of architecture known as "Grecian-Doric," "Roman-Doric," "Corinthian," "Ionic," and "Doric."

In the construction of our columns we may 35 provide the shaft thereof with a smooth exterior surface or we may provide each of the strips or sections from which the shaft is formed with exterior moldings or beads of any suitable configuration and which are 40 adapted to overlap the adjoining strip or section, so as to conceal the joint. We also flute the exterior of the columns in some constructions in order to obtain the desired effect on the exterior of the column-shaft, and in any 45 of these constructions the manner of interlocking the sections together is identical.

Another of the main objects of our invention is to obtain a much lighter column than is ordinarily employed, which is accomplished 50 by constructing the columns of a series of strips or sections which when interlocked together are rigidly held. By constructing

the columns of a thinner material the cost of the same is also materially decreased.

With the above and other objects in view 55 our invention further consists in the novel construction and arrangement, as will be hereinafter more specifically described, and particularly pointed out in the claims.

This invention should be considered in connection with an application filed by us May 10, 1897, Serial No. 635,969, and is an improvement thereon.

In describing the invention in detail reference is had to the accompanying drawings, 65 forming a part of this specification, wherein like numerals of reference indicate corresponding parts throughout the several views, in which—

Figure 1 is a perspective view of our improved column, the sections or strips being provided with exterior beads or moldings. Fig. 2 is a like view of a column constructed with a plain exterior. Fig. 3 is a horizontal sectional view of the shaft of the column 75 shown in Fig. 2. Fig. 4 is a like view of the shaft of the column shown in Fig. 1. Fig. 5 is a horizontal sectional view of a form of half-column, showing the application of the strips or sections. 80

In describing the invention in detail, reference being had to the drawings, the numeral 1 indicates the vertical strips of which the column is constructed. Each of the strips has on its one engaging face, and preferably 85 placed closer to the inner than to the outer face of the strip, an inclined tongue 2, the inclination of which is toward the exterior surface of the column-shaft. The strips are also provided on their other engaging face with an 90 inclined groove 3, corresponding in size and shape to the tongues 2, and which is adapted to receive the tongue of the adjoining section or strip. The construction of the tongues 2 at the inclination shown causes these tongues 95 to act as wedges when the strips or sections are interlocked together and to prevent any one of the strips or sections from being forced out of its position by either outward or inward pressure upon the same. 100

In Figs. 1 and 4 of the drawings we show the strips or sections 1 tongued or grooved in the same manner above described and provided on their exterior face with a half-round

bead or mold 4, which overlaps some distance upon the exterior surface of the next section and conceals the joint between the two sections.

- 5 The manner of assembling the strips or sections 1 to form the column-shaft, this assembling being done as desired or convenient either at the factory or place of using, is as follows: The tongues and sections, and also 10 the engaging faces of the strips or sections, if desired, are covered with glue or other adhesive substance and the tongue 2 of the one section is inserted in the groove 3 of the adjoining section, this arrangement being continued until but one strip or section is lacking to complete the column. Where the column-shaft is of an equal diameter from end to end, this remaining strip or section may be inserted from either end of the shaft; but 15 where the shaft is slightly tapered the remaining strip or section must be inserted into position from the larger end of the shaft and serves to firmly interlock and hold the strips or sections together.
- 20 25 In some cases the glue or other adhesive material employed may be omitted and the locking-joint employed to hold the strips or sections together. In general, however, we have found that it is preferable to employ the glue 30 in connection with the locking-joint, as it serves to render the joint more tight and impervious to the weather.

- 35 In the drawings we have shown both forms of column mounted upon a stylobate or pedestal 5 and provided with a capital 6, the latter being of that order known as "Corinthian." These parts, however, form no part of our invention, which is confined to the construction of the column-shaft.
- 40 45 50 In Fig. 5 of the drawings we show the application of the same construction for a half-column, 7 indicating the line of the wall. In this construction the bead 4 at one side of the column will be separate from the strip and will be in the form of a quarter-round strip, which can be fastened in position to give the complete finished appearance to the half-column in any desirable manner.

- We are aware of the patent to Beach, No. 50 211,291, for newel-post, which shows an octagonal post formed of sections or strips interlocking together by means of tongues and grooves, but in this construction the tongue is at direct right angles to the face of the

strip, while in our construction this tongue 55 extends outwardly toward the exterior of the column and is at an acute angle to the engaging face of the strip, so as to form a wedge when the strips are locked together.

What we claim as our invention, and desire 60 to secure by Letters Patent, is—

1. As a new article of manufacture, a hollow wooden column consisting of a series of substantially wedge-shaped sections which are interlocked together, the engaging faces 65 of said sections diverging outwardly in opposite directions and one of the engaging faces of each section provided with an integral tongue of equal thickness throughout having both of its side faces extending outwardly on 70 parallel planes at an acute angle to the engaging face with which the tongue is formed, the outer face of said tongue being parallel to the engaging face, the other engaging face of each section being provided with a groove 75 corresponding in shape to the tongue, the groove of one section being adapted to receive the tongue of the adjoining section, substantially as shown and described.

2. As a new article of manufacture, a hollow wooden column consisting of a series of substantially wedge-shaped sections which are interlocked together, the engaging faces of said sections diverging outwardly in opposite directions and one of the engaging faces 80 of each section provided with an integral tongue of equal thickness throughout having both of its side faces extending outwardly on parallel planes at an acute angle to the engaging face with which the tongue is formed, 90 the outer face of said tongue being parallel to the engaging face, the other engaging face of each section being provided with a groove corresponding in shape to the tongue, the groove of one section being adapted to receive 95 the tongue of the adjoining section, and a bead formed integral with the outer face of each section at one of its corners, the bead on one section overlapping on the adjoining section to conceal the joint, substantially as 100 shown and described.

In testimony whereof we affix our signatures in the presence of two witnesses.

ALBERT F. SCHWERD.
ASA W. EMRICK.
